UNITED STATES PATENT OFFICE.

MICHAEL J. SKORTZ, OF CLEVELAND, OHIO.

TOILET FLUSHER.

Application filed September 30, 1918. Serial No. 256,335.

To all whom it may concern:

Be it known that I, MICHAEL J. SKORTZ, a citizen of the United States, residing at Cleveland, in the county of Cuyahoga and 5 State of Ohio, have invented certain new and useful Improvements in Toilet Flushers, of which the following is a specification.

This invention relates to baths and 10 closets, and more especially to flush valves; and the object of the same is to produce a hand-operated valve for flushing a toilet bowl.

The invention comprises details in the 15 structure of the casing, the same being made in two separable parts which when disconnected give access to all the interior mechanism for cleaning and repair. Specifically, the invention lies in the shape of the valve 20 or plug and the seat with which it co-acts, as well as the shape of the casing and in the means for guiding the valve to its seat accurately. Details are set forth in the following specification and claim, and at 25 tention is drawn to the drawings, wherein:—

Figure 1 is a vertical section through the entire device, and

Figure 2 is a plan view of the valve seat removed.

30 The lower member of this device comprises a cup-shaped body 1, having a lateral inlet nipple 2 externally threaded and formed with a nut at 3, the open upper end of the body being surrounded by a flange 4, and its lower closed end carrying a depending barrel 5 whose bore opens into the interior of the body at the upper end of the barrel and is closed at the lower end by a pet cock 6 so that sediment within the 40 barrel may be drawn off from time to time. Sediment is likely to pass into the barrel 5 between the stem 31 and the inner wall of the barrel 5 and if no way is provided to remove this sediment, the opening of 45 the valve 30 will be retarded and in fact become very difficult.

The upper member includes a dome 11 whose larger lower end conforms to the size of the upper end of the lower member and is flanged as at 14, and whose smaller upper end is internally threaded as at 15, an arm 16 rising from the top of the dome and externally threaded and provided with a fixed nut as at 13. The 55 two members are assembled by placing the flange 14 upon the flange 4 and connect-

ing them by screws or bolts as indicated at 17, and it is obvious that when these are withdrawn, access is had to the interior of both members and all mechanism contained 60 therein.

Upward into the threads 15 is screwed an annulus 20 constituting a valve seat, its lower end being internally beveled as at 25 and its upper portion provided with a pair 65 of lugs 21 preferably opposite each other as shown in Figure 2. Therefore, when the lower member is removed from the upper member and the valve (described below) withdrawn, a suitable tool can be passed up 70ward into the valve seat and engaged with the two lugs and turned so as to unscrew the seat from the threads 15 and withdraw it entirely. The valve or plug 30 is in the shape of a double cone and made entirely of rubber. It is mounted on an up 75right stem 31 between an upper nut 32 and a lower nut 33, and when these are tightened up, it is obvious that the rubber plug-valve will be somewhat expanded. Its upper coni- 80cal portion contacts with the beveled portion 25 of the valve seat when the valve is closed as shown in Figure 1. The lower end of the stem is by preference slightly reduced as indicated at 35, and plays freely 85 in the bore of the barrel 5 which therefore serves as a guide for the same. The upper portion of the stem is not threaded. It passes throughout the length of the arm 16 in the casing, and out through the upper 90 end of the latter where it is surrounded by packing 18 held in place by a gland nut 19. On the upper extremity of the stem is a knob 36 which is removable in an easy manner. It may be screwed onto the stem or 95 may be held by a set-screw as shown at 37. A light expansive spring 38 is coiled around the lower portion of the stem between the lower nut 33 and the upper end of the barrel 5. I have described this valve as an 100 entirety as standing upright and such is the illustration in Figure 1, but I wish it to be understood that it might stand horizontal.

The action is as follows:—

Water flowing in as indicated by the arrows enters the body 1 and assists the spring 38 in holding the valve plug 30 upward against its seat, while the interior of the arm 16 and nipple 12 are open to the 110 outlet which in the present case would be the bowl of a toilet. When now the operator

desires to flush the bowl, he has but to press on the knob 36. This moves the stem 31 downward and compresses the spring 38, unseating the valve 30 and depressing it to 5 about the position shown in dotted lines in Figure 1. The water within the body now immediately flows around the largest diameter of the plug and rushes upward through the annulus 20, throughout the length of the 10 arm 16, and out the nipple 12 to the bowl or other point of use. When the valve 30 is pushed downwardly to the position shown in dotted lines in Fig. 1, the weight of the valve and also the weight of the stem 31 15 will tend to retain the valve 30 in this dotted position until the spring 38 gradually forces the valve upwardly to a closed position as is shown in full lines. The passage of the water over the valve will also assist in causing 20 the valve 30 to move to a closed position at a slow rate of travel. It will therefore be seen that the valve will remain in an open or partly open position for some little time, thereby eliminating the necessity of maintaining 25 pressure upon the knob 36 in order to cause a supply of liquid to pass through the valve for a short period of time. Furthermore it will be noted that the part 5 acts as a dash-pot for the valve stem, the latter 30 fitting closely in the part 5. Moreover, the pet cock 6 may either be opened to allow free action of the stem or closed to produce the dash-pot effect.

For this reason the spring 38 need not be 35 a very strong one. In the longitudinal movement of the stem 31 its lower end 35 is guided in the barrel and its upper portion is guided through the packing 18 and gland 19, and therefore the valve is always centered 40 through the annulus and its upper conical portion will always fit accurately within the beveled lower end 25 which constitutes the valve seat. Nevertheless, when it is desired to grind or clean this seat, the 45 entire annulus can be removed in a manner above set forth. In fact, whenever access to the interior of this flush mechanism is desired for any purpose the two members can be readily separated by withdrawing the 50 bolts or screws 17. This knob 36 will then be removed and the entire valve and its stem

taken out of place in a manner obvious to any plumber.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claim.

Having thus described my invention, what I claim as new and desire to secure by Letters Patent is:—

In combination, a casing constituting a valve body and having an open top, a dash pot forming part of said casing at the bottom thereof, a combined valve and drain cock at the lower end of said dash pot, an 70 outlet nipple communicating laterally with the casing, a dome on the top of the casing removably secured thereto and closing said top, an outlet nipple extending laterally from the dome, the lower portion of said dome being frusto conical in form, the dome immediately above the frusto conical form being cylindrically formed and internally threaded, a valve seat screwed into the internally threaded portion and having an 80 opening therethrough frusto conical at its lower end, a stem extending downward through said dome into said dash pot, the metal portion of said stem being threaded for a considerable portion of its length, a 85 valve mounted on said threaded portion and having a frusto conical upper end and an inverted frusto conical lower end, nuts on said stem above and below said valve for adjusting the valve longitudinally of the stem, a 90 coil spring surrounding the stem and having its lower end resting on top of the dash pot and its upper end engaging the lower side of the nut below the valve, and a handle on the upper end of said stem.

In testimony whereof I affix my signature in presence of two witnesses.

MICHAEL J. SKORTZ.
